Primary Examiner — Jennifer L Rempfer

(57) **CLAIM**

The ornamental design for a wedge pillow set, as shown and described.

DESCRIPTION

FIG. 1 is a perspective view of a wedge pillow set showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view thereof;

FIG. 10 is a perspective view of the wedge pillow set where the wedge pillow set is in a first configuration of use;

FIG. 11 is a perspective view of the wedge pillow set where the wedge pillow set is in a second configuration of use; and, FIG. 12 is a perspective view of the large triangular portion of the wedge pillow set in a third configuration of use.

The broken lines in the drawings depict environments of the wedge pillow set that form no part of the claimed design.

1 Claim, 12 Drawing Sheets
